UNITED STATES PATENT OFFICE

JOSEPH HRNCSJAR, OF HOMEWOOD, ILLINOIS

COMBINATION WOOD SAWING MACHINE

Application filed September 9, 1929. Serial No. 391,240.

This invention relates to wood sawing machines and more particularly to machines of this character having embodied therein a plurality of rotary wood cutting elements which are arranged in a novel and compact manner on a supporting frame and in relation to a work table in a manner to perform cutting off and dado cutting operations on building material, such as window frames and sills and box frames, and it is also to be understood that the machine may be used for dado work on door jambs.

An important object of the invention is to provide, in a manner as hereinafter set forth, a wood working machine of the aforementioned character wherein the several elements are provided with driving motors and mounted in the frame in a manner to shift or adjust the rotary cutters toward or from the work and wherein said cutters may be independently adjusted.

Other objects of the invention are to provide a wood working machine of the character set forth which will be simple in construction, strong, durable, efficient in its use, and which may be manufactured at low cost.

Other objects and advantages of the invention will become apparent from a study of the following specification, taken in connection with the accompanying drawings, wherein like characters of reference designate corresponding parts throughout the several views, and wherein:

Figure 1 is a front elevation of a wood working machine constructed in accordance with this invention.

Figure 2 is a top plan view thereof.

Figure 3 is a cross sectional view, taken on the line 3-3 of Figure 2.

Figure 4 is an elevation of one of the strips of wood, showing several cuts formed therein by this machine.

Figure 5 is a horizontal section of the vertically adjustable supporting means for the upper supporting frame and taken on the line 5-5 of Figure 1.

Figure 6 is a sectional view, taken on the line 6-6 of Figure 2.

Figure 7 is a vertical fragmentary sec-

tional view taken approximately on line 7-7 of Figure 3.

Referring to the drawings in detail, the reference character 1 designates generally a supporting frame having the base portion 2, vertical posts 3, and the work supporting table 4 mounted on the upper ends of the post 3 and extending forwardly therefrom in superposed spaced relation with respect to the base portion 2.

A power driven rotary saw 5 is journaled in the upper end of a frame 6 which is mounted for vertical adjustment between the adjacent posts 3 of the frame through the medium of the rearwardly extending bars 7, which diverge from the substantially U-shaped frame 6, to the opposed sides of the adjacent posts 3 and are joined, at their rear ends, to the cross bar 8 having upturned end portions 9, slidably disposed in grooves 9' in said posts. An electric motor 10 is mounted on the cross bar 8 and is provided with a pulley 11 from which a drive belt 12 extends over a pulley 13 on the saw 5 for the purpose of rotating same. At its lower end, the U-shaped frame 6 is provided with downwardly extending spaced legs 14, for the purpose of connecting a foot actuated lever 15 thereto through the medium of the pin and slot connections 16, as clearly shown in Figure 3. The lever 15 is journaled between the upper ends of a pair of spaced standards 17, which are mounted on the forward portion of the base 2. The lever 15 constitutes means for lifting the frame 6, the saw 5, the bars 7, the cross bar 8 and the motor 10 as a unit in a vertical plane, the end portions 9 sliding in the grooves 9'.

A supporting rest 18' is provided for engagement by the lever 15 for supporting the forward end of the frame when said frame is in its lowered position. The cut off saw 5 is normally below the surface of the table 4 and is adapted to be projected through a slot 18 in said table, when elevated, through the medium of the foot lever 15. The pulley 13 is journaled between the upper ends of the U-shaped brackets 6 through the medium of the horizontal shaft 19, which extends laterally beyond one of the legs of the

frame 6, and the saw 5 is mounted on the free outer end thereof, as clearly shown in Figure 1 of the drawings.

A pair of spaced dado cutters 20 are mounted for rotation in the forward end and on opposite sides of a supporting frame 21, and an electric motor 23 is mounted in the rear end of said frame, the rear end of which is slidably mounted on an inclined rockable supporting platform 22 mounted between the adjacent posts 3. The motor 23 rotates the dado cutters 20 through the medium of the endless belt 24 extending over a pulley 25 fixed on a shaft 26 on one side of the frame 21. The dado cutters 20 are mounted on the shaft 26 in the frame 21 and a spacing sleeve 26' is mounted on said shaft between said cutters. The opposite ends of the shaft extend laterally beyond the frame into an elliptical groove 27 in each of the adjacent horizontal table supports 28. A hand gripped lever 29 is mounted on the frame 21 and is grasped by an operator through an opening 30, see Figure 2, in the table top for drawing the cutters 20 upwardly through slots 31 in an arcuate sweep.

A frame similar to the one supporting the saw 5 and designated generally by the reference character A is mounted on the right side 32 of the frame 1. The vertical portion 33 of this frame is provided with a turntable 34, upon which is rotatably mounted an electric motor 35, having a rotary cut-off saw 36 mounted thereon. Above the saw 36, the table 4 is provided with right angularly disposed intersecting slots 37, through which the saw 36 is adapted to be selectively projected when elevated through the medium of the foot lever associated therewith, said lever and its mounting means being a duplicate of that of the lever 15.

Extending vertically from the rear marginal portion of the table 4, are a plurality of pairs of vertical posts 38, having dove tailed forward faces 39 thereon for slidably engaging the complementary vertically adjustable extensions 40, in which the opposite ends of the horizontal cross bars 40' are mounted. The upper ends of the extensions 40 are provided with forwardly extending right angularly disposed horizontal arms 41, the opposed faces of which pairs of arms 41 are provided with channels of the cross sectional shape indicated in Figure 6 of the drawings. The aforesaid channels are indicated by the reference character 42. A brace 43 has its opposite ends connected to the extension 40 and the arm 41.

A pair of horizontal platforms 44 have their opposite ends extending into the channels 42, in each pair of the arms 41 and terminate at their opposite sides in downturned portions 45 for engagement with the ball bearings 46 which are positioned in the channel 42. It will thus be seen that the plat-

forms 44 are adapted to be shifted longitudinally in the channels 42 of the arms 41.

A suspension frame 47 depends from each of the platforms 44 and journaled in said frames 47, adjacent their lower ends, are the transverse shafts 48, the opposite ends of which extend outwardly beyond the sides of the frames 47 and have mounted thereon pairs of cutters 49 and 53. As indicated in Figure 1 of the drawings, the frames 47 are substantially U-shaped in configuration and mounted therein on the shafts 48 are the drive pulleys 49', (see Figure 3). Electric motors 50 are mounted on the platforms 44 and have the pulleys 51 for the purpose of driving the cutters 49 and 53 through the medium of the endless belts 52, the lower ends of which extend around the pulleys 49'.

The construction of the two upper units is identical with the exception that the members 49 are dado cutters and the members 53 are disk saws spaced a greater distance apart than members 49.

A substantially U-shaped handle 54 is anchored to each of the frames 47 for the purpose of shifting the same forwardly and rearwardly on the arms 41. For the purpose of adjusting the upper frames and the cutters thereon vertically, a pair of vertical screw shafts 55 are rotatably mounted on horizontal supporting bars 56 of the frame and are threaded through the cross bars 40' of the upper frames and said shafts are provided with actuating handles or levers 57 on their upper ends. When the shafts are rotated, the frames will be shifted vertically, as will be apparent.

I have thus provided a machine which is adapted to perform practically all of the cutting operations necessary for use in making window frame heads and sills, as well as box frames.

It is believed that the many advantages of a wood sawing machine constructed in accordance with this invention will be readily understood and although the preferred embodiment of the invention is as illustrated and described, it is to be understood that changes in the details of construction may be had, which will fall within the scope of the invention as claimed.

What is claimed is:

1. A wood sawing machine of the character described comprising a work supporting table having an intermediate slot and a pair of outer slots disposed parallel with said intermediate slot on the opposite sides thereof, a pair of spaced, rotary dado cutters mounted for movement in a horizontal plane above the table for operable engagement with the work thereon, a pair of spaced rotary dado cutters shiftably mounted beneath the table and operable through the outer slots for engagement with the work, a rotary cut-off saw mounted for vertical

- movement beneath the table and operable through the intermediate slot for engagement with the work.
2. A wood sawing machine of the character described comprising a work supporting table having an intermediate slot and a pair of outer slots disposed parallel with said intermediate slot on the opposite sides thereof, a pair of spaced, rotary dado cutters mounted for movement in a horizontal plane above the table for operable engagement with the work thereon, a pair of spaced rotary dado cutters shiftably mounted beneath the table and operable through the outer slots for engagement with the work, a rotary cut-off saw mounted for vertical movement beneath the table and operable through the intermediate slot for engagement with the work, means operatively connected with the cut-off saw for manually shifting same vertically and guide means operatively connected with the second named pair of dado cutters whereby same move substantially in an arcuate path through their respective slots.
- 25 3. A wood sawing machine of the character described comprising a work supporting table having an intermediate slot therein and a pair of outer slots disposed in spaced, parallel relation with the intermediate slots on the opposite sides thereof, a supporting structure disposed above the table, a pair of spaced rotary dado cutters suspended from the supporting structure for movement in a horizontal plane thereon and adapted for operable engagement with the work on the table, means for adjusting the supporting structure in a vertical plane, a pair of rotary spaced dado cutters shiftably mounted beneath the table and operable through the outer slots for engagement with the work on the table, guide means operatively connected with the second named dado cutters whereby same move substantially in an arcuate path through their respective slots, a rotary cut-off saw mounted for vertical shifting movement beneath the table and operable through the intermediate slot for engagement with the work, means for manually shifting the cut-off saw in a vertical plane.
- 45 4. A wood sawing machine of the character described comprising a work supporting table having an intermediate slot therein and a pair of outer slots disposed in spaced, parallel relation with the intermediate slots on the opposite sides thereof, a supporting structure disposed above the table, a pair of spaced rotary dado cutters suspended from the supporting structure for movement in a horizontal plane thereon and adapted for operable engagement with the work on the table, means for adjusting the supporting structure in a vertical plane, a pair of rotary spaced dado cutters shiftably mounted beneath the table and operable through the outer slots for engagement with the work on
- the table, guide means operatively connected with the second named dado cutters whereby same move substantially in an arcuate path through their respective slots, a rotary cut-off saw mounted for vertical shifting movement beneath the table and operable through the intermediate slot for engagement with the work, means for manually shifting the cut-off saw in a vertical plane, driving means operatively connected with the first named dado cutter and shiftable in unison therewith, drive means operatively connected with the second named pair of dado cutters and shiftable in unison therewith, drive means operatively connected with the cut-off saw and shiftably vertically in unison therewith.
5. A wood sawing machine of the character described comprising a work supporting table having intersecting slots therein disposed substantially at right angles to each other, a pair of spaced, parallel rotary cutters mounted for shifting movement in a horizontal plane above the table for operative engagement with the work thereon, and a rotary cutter mounted for vertical movement beneath the table and selectively operable through the slots for engagement with the work.
6. A wood sawing machine comprising a work supporting table having a pair of slots therein disposed at an angle relative to each other, a supporting structure above the table, a pair of spaced, rotary cutters suspended from the supporting structure for movement in a horizontal plane and operatively engageable with the work on the table, a turntable, a rotary cutter supported by the turntable and arranged for vertical shifting movement therewith, said cutter being selectively operable through the slots for engagement with the work on the table, and means for shifting the turntable vertically.
- In testimony whereof I affix my signature.
- JOSEPH HRNCSJAR.
